UNITED STATES PATENT OFFICE.

JOHN M. HOPWOOD, OF DORMONT, PENNSYLVANIA.

STOKING MECHANISM.

1,400,548.

Specification of Letters Patent. Patented Dec. 20, 1921.

Application filed February 20, 1918. Serial No. 218,269.

To all whom it may concern:

Be it known that I, JOHN M. HOPWOOD, residing at Dormont, in the county of Allegheny and State of Pennsylvania, a citizen 5 of the United States, have invented or discovered certain new and useful Improvements in Stoking Mechanism, of which improvement the following is a specification.

The invention described herein relates to 10 certain improvements in stoking mechanism, such improvements being especially applicable to the type or construction of furnace having a trough extending from the front to the rear of the furnace, into which the 15 fuel is fed in such manner as to overflow the sides of the trough onto the fuel supporting surfaces extending in opposite directions from the respective edges of the trough, the fuel being caused to move along the grate 20 surfaces toward the ash pits by the reciprocation of portions of such surfaces. The object of the improvements described herein is to provide for the forcing of fuel into the trough by a reciprocating ram or plunger 25 and for the reciprocation of the movable members of the grate surfaces in directions at an angle to the movement of the feed plunger, by the latter or parts moving synchronously therewith. The invention is 30 hereinafter more fully described and claimed.

In the accompanying drawing forming a part of this specification, Figure 1 is a view partly in front elevation and partly in section of a furnace embodying the improvements described herein; Fig. 2 is a sectional plan view of the front of the furnace, the plane of section being indicated by the lines 35 II-II, Fig. 1; Fig. 3 is a sectional elevation, the plane of section being coincident with the axis of the fuel trough and indicated by the lines III-III, Fig. 1. Fig. 4 is a sectional elevation on a plane indicated by the line IV-IV, Fig. 3, showing a preferred construction of fuel trough, and fuel supporting surfaces, the fuel pushing blocks being omitted; and Fig. 5 is a sectional detail view.

In the practice of the invention, the fuel is fed into the open upper end of a hopper 1 50 of the usual or any suitable construction. This hopper is arranged in front of the furnace and connects at its lower end with a throat piece 2 preferably cylindrical in cross section, projecting through the front wall of 55 the furnace in line with the feed trough 3, which is arranged longitudinally of the fur-

nace. A shell 4 is arranged in front of the throat 2 and if desired may be formed as an extension thereof and within the shell is arranged a plunger 5 adapted to be reciprocated by the piston of a fluid pressure cylinder 6 or any other suitable means. The plunger, except when operated to force fuel through the throat into the trough, occupies such a position in the shell that the fuel will 60 drop from the hopper into the throat filling the portion of the same in front of the plunger. As the latter moves forward, forcing fuel in the throat, it will close the opening from the hopper into the throat. 65

In order to prevent the fuel from piling up in the front portions of the trough, means are provided for effecting a practically uniform distribution of the fuel along the trough, such for example as a series of push blocks 70 7 secured to a rod 8 extending along the trough in such relation to the bottom that the lower ends of the blocks will bear upon and move along the bottom of the trough. The rod 8 is connected to an arm 9 movable 75 synchronously with the plunger and preferably secured thereto so that as each charge is forced into the trough, the fuel lying therein is moved along to maintain a uniform distribution. The fuel is fed in and 80 distributed until it is piled above the edges of the trough and will spread laterally onto the ends of the fuel supporting surfaces, consisting of stationary and movable members, preferably constructed as shown and 85 described in Letters Patent No. 1,319,584 dated October 21st, 1919, to John M. Hopwood.

In the construction shown herein the stationary grate bars *a* are spaced suitable 90 distances apart and the spaces between said bars are bridged by the heads *b* of the movable bars, the web *c* of the latter extending down between adjacent stationary bars. These webs are provided with teeth which 95 intermesh with teeth on beams *d* carried by arms 10 on shafts 11. These shafts are supported in suitable bearings below and at an angle to the direction of movement of the movable members of the fuel supporting 100 surfaces. The ends of these shafts which project through the front of the furnace, have arms 12 secured thereto, the free ends of said arms being engaged by slides 13 adapted to be reciprocated by the fuel feeding mechanism. A convenient means for 105 reciprocating the slides (which move par-

allel with the front of the furnace) by the feed mechanism which reciprocates at an angle to the front of the furnace and to the means employed for rocking the shafts 11, 5 is shown in Figs. 1, 2 and 3 of the drawings and consists of toothed bars 14 suitably connected to a movable member of the feed mechanism, as the plunger 5, the connection between the plunger and bars being 10 formed by arms 15 projecting through slots 16 in the shell 4. These toothed bars which are supported by the arms substantially parallel with the axis of the plunger, engage pinions 17 on short shafts 18 mounted 15 in bearings on the front of the furnace and having secured thereon pinions 19 adapted to engage toothed portions 20 of the slides 13. The connections of the slides with the arms 12 are preferably made 20 adjustable in order to change the range of movement of the movable members of the fuel supporting surfaces without changing the movements of the slides. While other means would readily suggest themselves to 25 one skilled in the art, the construction shown is suitable and consists in forming a series of holes 21 in the slides for the reception of pins 22 on the opposite sides of the arms 12. By shifting the positions 30 of the pins on the slides the range of movement of the movable grate members can be changed as conditions in the furnace may require, as also the time of movement of such members relative to the operation of 35 the fuel feed mechanism, *i. e.*, simultaneous with such operation or following an initial movement of the feed mechanism.

As will be understood by those skilled in the art, the slides 13 can be employed for 40 operating other devices in the furnace such as oscillating the ash supporting plates 23, each of which has one edge pivotally connected to a suitable support, while its opposite edge is supported by arms 24 on the 45 shaft 25. On these shafts are secured arms 36 which are connected by links 37 to arms 38 on shafts 39, which are rotated by worms 40 engaging toothed sectors 41 secured on said shafts, as shown in Figs. 1 and 4. By 50 the rotation of said shafts 39, the angular positions of the ash plates can be changed as desired. The positions of these plates are shown by index fingers 42 secured to 55 shafts 39, whereby they are shifted along scales 43. The reciprocation of the ash plates relative to the fuel supporting members is effected by the reciprocation of the slides 13, through the medium of arms 26, each having one end secured on a shaft 25^a 60 and their opposite ends adjustably connected to the slides by pins 27 adapted to be inserted in holes 28 in the slides. The shafts 25^a are provided with arms 26^a which are connected by links to the ash plates as 65 shown in Fig. 4. By suitably arranging the

pins, the range of movement of the ash plate and its time of movement relative to the operation of the feed mechanism and the reciprocation of the movable member, can be readily and quickly changed. 70

In order to regulate the movement of the coal through the hopper and into the throat of the feed trough, an opening is formed in a wall of the hopper, preferably the rear wall and in this opening is hung a swinging 75 gate 29, preferably provided with a bottom plate 30 to prevent the coal from being forced up back of the gate and through the opening. Any suitable means may be employed for shifting the gate and holding it 80 in any desired position, such for example as that shown consisting of threaded rods 31 having their rear ends swiveled to laterally projecting lugs 32 on the gate and extending forwardly through threaded openings in lugs 33 in the hopper. By rotating these threaded rods the gate can be shifted and held in any desired position.

The hopper is also provided with a slide 34 at or adjacent to its lower end for the 90 purpose of preventing coal from entering the throat; and in order to facilitate the removal of coal from the hopper, a door 35 is arranged in the side wall as shown in Fig. 3. 95

It will be observed by reference to Fig. 3 that the front face of the plunger 5 is dished, thereby forming a peripheral cutting edge which assists in breaking up lumps of coal lodging between the hopper wall and the 100 plunger.

I claim herein as my invention:

1. In a stoking mechanism the combination of means for feeding fuel into a furnace, fuel supporting means having members movable longitudinally to advance the fuel in a direction at a right angle to the direction of the feed of fuel, an ash supporting plate movable in the same direction as the fuel supports and connections from the 110 fuel feeding means to the movable members of the fuel supporting means and to the ash plate and adapted to reciprocate the fuel supporting means and the ash plate simultaneously. 115

2. In a stoking mechanism the combination of a reciprocating plunger for feeding fuel into a furnace, fuel supporting means having members movable longitudinally in a direction to advance the fuel at an angle 120 to the movement of the plunger, a movable ash plate means for adjusting the angular position of the ash plate and means operative by the plunger for reciprocating the movable fuel supporting means and the ash 125 plates without changing the angular position of the ash plate.

3. In a stoking mechanism the combination of a trough, means for feeding fuel into the trough, fuel supporting means extend- 130

ing in opposite directions from the trough and having movable elements for advancing the fuel along said supporting means, movable ash plates and adjustable connections from the fuel feeding means to the movable elements of the fuel supporting means and to the ash plates, whereby the movable elements and one of the ash plates on one side of the trough may be given 5 movements differing as regards the extent, position and occurrence from the movements of the movable elements and the other ash plate on the opposite side of the trough.

4. In a stoking mechanism the combination of fuel supporting means having movable elements for advancing fuel along such means, a movable ash plate, means for feeding fuel upon the supporting means, means adapted to be operated by the fuel feeding 15 means for operating said movable elements and the ash plate, and independent and adjustable connections from the movable elements and the ash plate to their operating means whereby the movable fuel advancing 20 elements may be given a movement differing as regards range and occurrence from the movement imparted to the ash plate.

5. In a furnace the combination of a series of stationary grate bars, a series of movable 30 grate bars alternating with the bars of the other series, an ash supporting member, a reciprocating member, independent and adjustable connections from the movable grate bars and the ash supporting member to the reciprocating member, whereby the movable 35 grate bars may be given a movement differing as regards range and occurrence from the movement imparted to the ash supporting member.

40 6. In a furnace the combination of a trough or retort, means for feeding coal into said retort, a fuel supporting means consisting of alternating stationary and movable grate bars arranged at an angle to the direction of movement of coal in to the retort, a slide, means for reciprocating the slide in a direction at an angle to the movement of the fuel into the retort by the coal feeding means and adjustable connections 45 from said slide to the movable grate bars whereby the movable grate bars on one side of the trough may be given a movement differing as regards extent, position and occurrence from the movement imparted to the 50 bars on the other side of the trough.

55 7. In a furnace the combination of a trough or retort, reciprocating means for forcing coal into the retort, a fuel supporting means consisting of alternating stationary and movable bars arranged at an angle to the direction of movement of the fuel into

the retort, a movable ash supporting member, a slide bar adapted to be reciprocated by the fuel feeding means and independent and adjustable connections from the movable bars and ash supporting member to the reciprocating slide bar.

65 8. In a stoking mechanism the combination of a trough, means for feeding fuel into the trough, fuel supporting means extending 70 from opposite sides of the trough and having movable members for advancing the fuel, a motor, independent and adjustable connections embodying intermeshing toothed elements operating interposed between the 75 motor and the movable members of the respective fuel supporting means whereby movements differing as regards extent, position and occurrence may be imparted to the movable members of the respective fuel sup- 80 porting means.

9. In a stoking mechanism the combination of a trough, means for feeding fuel into the trough, fuel supporting means extending in opposite directions from the 85 trough, and having movable elements for advancing fuel along the fuel supporting means, a pair of toothed bars adapted to be reciprocated by the fuel feeding means, a second pair of toothed bars arranged substantially parallel with the fuel supporting means, vertical shafts having pinions engaging respectively the two sets of toothed bars, shafts provided with means for engaging the movable fuel supports, arms secured to the last named shafts and adjustable means on the second set of toothed bars for engaging said arms.

95 10. In a stoking mechanism the combination of a trough, means for feeding fuel into and along the trough, fuel supporting means extending in opposite directions from the trough and having movable elements for advancing fuel along the fuel supporting means, a movable ash supporting plate, a 100 pair of toothed bars adapted to be reciprocated by the fuel feeding means, a second pair of toothed bars arranged substantially parallel with the fuel supporting means, vertical shafts having pinions adapted to engage the two sets of toothed bars, horizontal 105 shafts having operating connections to the movable elements of the fuel supporting means and the ash supporting plate, arms secured to said horizontal shafts and adjustable means on the second pair of toothed bars for engaging and shifting the said 110 arms.

115 In testimony whereof, I have hereunto set my hand.

JOHN M. HOPWOOD.
